UNITED STATES PATENT OFFICE.

CABEL B. HOPKINS, OF PHILADELPHIA, PENNSYLVANIA, ASSIGNOR TO THE ENTERPRISE MANUFACTURING COMPANY OF PENNSYLVANIA, OF SAME PLACE.

SHARPENING ATTACHMENT FOR MEAT-CUTTERS.

SPECIFICATION forming part of Letters Patent No. 680,148, dated August 6, 1901.

Application filed September 20, 1899. Serial No. 731,088. (No model.)

To all whom it may concern:

Be it known that I, CABEL B. HOPKINS, a citizen of the United States, residing in Philadelphia, Pennsylvania, have invented certain 5 Improvements in Sharpening Attachments for Beef-Shaving Machines, of which the following is a specification.

The object of my invention is to sharpen the blade of a machine for cutting or shaving meat, &c., having an oscillating knife, without removing the blade from the machine, and this object I attain in the following manner, reference being had to the accompanying drawings, in which—

15 Figure 1 is an end view of a beef-shaver with my improved blade-sharpener attached. Fig. 2 is a view of a portion of the side of the machine, showing the sharpener shifted clear of the blade. Fig. 3 is a side view, partly 20 in section, showing the sharpener resting against the blade; and Figs. 4 and 5 are detached perspective views showing the details of the sharpening mechanism.

A is the frame of the machine.

25 B is the knife-frame, pivoted at b to the upper portion of the frame A.

A' is a V-shaped trough in which the beef to be shaved is placed. The knife is so pivoted that it shears past the end of the trough 30 and cuts the beef as it is fed forward by the feed mechanism of the machine.

My invention does not relate to the construction of the beef-shaving machine, and the above is simply the description of the 35 form of machine to which my invention may be applied.

In machines of the type described above it is a difficult matter to sharpen the knife-blade. Heretofore this has been done by 40 hand, either by drawing the knife-frame back as far as it will go and sharpening the blade while in that position or the blade was removed and sharpened.

My invention relates to sharpening mechanism attached to the machine, which can be thrown into or out of operation without interfering materially with the working of the machine, and which will accurately sharpen the blade.

45 D is a block secured to the base of the

frame A, but which may form part of the frame in some instances. Pivoted at d to this block is a carrier-lever D', to one arm of which is attached a sharpener d' of any suitable form, being shaped in the present instance similar to an ordinary butcher's steel. A spring c, secured to the block D, rests against the other arm of the lever D' and tends to keep the sharpener d' in contact with the blade during the time the device is 55 in position to sharpen the blade, thus insuring a yielding contact, and when the device is thrown out of gear the spring tends to keep it out of the path of the knife-frame.

E is a shifter pivoted to the frame A at e, 65 and is shaped to conform to the outline of the frame. This shifter has a projection e', which can be moved to either side of the frame, and preferably rests in recesses a a' formed in the frame. There is a sufficient 70 spring in the metal of the shifter to allow it to be set in either position. On the shifter is a stop e'', against which strikes the knife-frame B when it is moved forward, so as to limit the forward movement of the knife-frame when the sharpener is in position to 75 sharpen the blade, but when the shifter is moved back, so as to allow the sharpener to clear the blade, the stop is also clear of the knife-frame. 80

I claim as my invention—

1. The combination in a shaver or cutter for meat, &c., of a knife having a beveled edge with a sharpening device constructed to be brought into yielding contact with the beveled portion of the knife, and means for normally holding said device on the side of the blade opposite to that having said beveled edge and out of the path thereof, substantially as described. 90

2. The combination in a shaver or cutter for meat, &c., of a knife having a beveled edge, a pivoted sharpener adapted to rest against said edge, a spring tending to keep the sharpener in contact with the blade when 95 the edge thereof is being sharpened, said spring normally tending to keep the sharpener out of the path of the blade, substantially as described.

3. The combination in a shaver or cutter 100

for meat, &c., of a knife having a beveled edge, a pivoted lever having a sharpener on one arm, a spring bearing against the other arm of the lever, and a pivoted shifter adapted to throw the sharpener into the path of the knife, said spring being arranged to press the sharpener device into yielding contact with the knife when the said device is in gear and to keep the said sharpener out of the path of the knife-frame when the device is out of gear, substantially as described.

4. The combination of a shaver or cutter

for meat, &c., having an oscillating blade, a pivoted lever carrying a sharpener, and a pivoted shifter for said sharpener, said shifter having a stop to limit the movement of the blade, substantially as described.

In testimony whereof I have signed my name to this specification in the presence of two subscribing witnesses.

CABEL B. HOPKINS.
